UNITED STATES PATENT OFFICE.

ROBERT PORTER, OF YOUNGSTOWN, OHIO.

MACHINE FOR THE MANUFACTURE OF TWISTED BARS.

1,152,759.

Specification of Letters Patent.

Patented Sept. 7, 1915.

Application filed March 31, 1911. Serial No. 618,231.

To all whom it may concern:

Be it known that I, ROBERT PORTER, residing at Youngstown, in the county of Mahoning and State of Ohio, a citizen of the 5 United States, have invented or discovered certain new and useful Improvements in Machines for the Manufacture of Twisted Bars, of which improvements the following is a specification.

10 The invention described herein relates to certain improvements in twisting bars to form binders for cement structures and other purposes, and the invention has for its object the twisting of the bar as it passes 15 from the last pass of the reducing rolls.

The invention is herein-after more fully described and claimed.

In the accompanying drawing forming a part of this specification Figure 1 is a side elevation of a stand of rolls having my improvement applied thereto; Fig. 2 is a top plan view of the construction shown in Fig. 1. Fig. 3 is a sectional view on an enlarged scale, showing the twisting head, the reducing rolls and guides; Fig. 4 is a front elevation of the twisting head; Fig. 5 is a detail view illustrating the mechanism for controlling the rotation of the twisting head; Fig. 6 is a view similar to Fig. 4, illustrating a modification of my improvement; Fig. 7 is an end view of a die and Fig. 8 is an inside plan view of the inside of the die.

While the twisting mechanism may be supported in any suitable manner it is preferred to attach the supporting frame to the housing 1 of the last stand of rolls of the bar-mill. This frame consists of side pieces 2 bolted to the housing and connected by cross pieces 3. To the cross pieces are attached the uprights 4 which serve to support the bearings 5 for the journal 6 of the twisting head 7 and the bearings 8 for the countershaft 9. This shaft is driven through bevel gears 10 by the shaft 11, which in turn is driven in any suitable manner preferably by a chain 11^a from the neck of one of the reducing rolls as clearly shown in Figs. 1 and 2. A pinion 12 on the countershaft 9 intermeshes with a toothed wheel 13 formed on or secured to the hollow journal 6 of the twisting head. This head is provided with suitable means for engaging the bar or rod in such manner as to turn the same axially and to permit of the bar being forced through the head after being twisted.

A convenient form of grippers consists of

radially movable jaws 14 mounted in the twisting head as shown in Figs. 3 and 4. A convenient means for shifting the jaws radially consists of a sleeve 15 movably mounted in the head and provided with bent fingers 16 engaging the jaws. This sleeve is shifted back and forth along the head to open and close the jaws by a lever 17, which can be operated in any suitable manner preferably by a solenoid 18 or other form of motor capable of being controlled by or in accordance with the movement of the bar operated on.

The bar is directed into the pass in the 70 rolls by the usual or any suitable form of guide 19 and from the rolls the bar passes through a holding guide 30 having a portion formed with an internal shape corresponding to the cross sectional shape of the bar 75 and adapted to prevent the portion of the bar adjacent to the rolls from turning axially but permitting of its longitudinal movement by the rolls. As indicated in Fig. 3, the circuit of the solenoid includes two make 80 and break devices 21 and 22, one arranged to be controlled by the bar before it enters the rolls and the other so arranged that it will be closed to excite the solenoid, at such a time with reference to the inward movement 85 of the bar that the jaws will not be closed until the front end of the bar has passed a short distance between them. These make and break devices are conveniently formed by contact springs which normally stand 90 apart and are adapted to be closed by pivotally mounted dogs 23 and 24 so mounted on the guides that their tails project into the path of the movement of the bar. As the bar passes along the guide 19, it will shift 95 the dog 23 and close the contact 21, and as the front end of the bar approaches the twisting head, it will shift the dog 24 to close the contact 22 thus completing the circuit of the solenoid.

After the bar has been gripped by the jaws, a complete or partial revolution is given to the head 7. This movement as before stated being imparted to the head by the rolls through the chain 11^a and sprocket 105 wheel 11, provision should be made for checking such movement as required. To this end the sprocket wheel is secured to a sleeve 26 loosely mounted in the shaft 11 and having its inner end provided with a 110 member of a clutch device, the other member of the clutch being formed as a collar 27

keyed to but movable along the shaft. This collar is engaged by one arm of a bell crank lever 28, the other arm being detachably connected to the core of a solenoid 29 preferably so connected with the circuit of the solenoid 18 as to be controlled by the make and break devices 21 and 22, as indicated in Fig. 5. In order that the lever 28 may be disconnected from the core 30 of the solenoid, as soon as the clutch members are in engagement, the connection between the core and the lever 28 is formed by a hook 31 pivotally connected to the core and adapted to engage a pin 32 on the lever. The disengagement of the hook from the pin may be effected in any suitable manner, as for example the hook may be formed with a cam 33, which as the core is shifted, will move along an abutment 34 and after a predetermined movement of the lever cause the hook to be shifted from engagement with the pin 32. In order to keep the clutch members in engagement with each other after the hook has been shifted the collar 27 is provided with a lug 35, which, while the clutch members are separated, will extend into a recess in a bearing 36 of the shaft 11. One wall of the recess is inclined as shown in Fig. 5 and as soon as the clutch members engage and the collar 27 begins to rotate the lug 35 will move along the inclined wall of the recess moving the clutch members into further engagement, in which position they are held against the pull of the spring 37 by the bearing of the lug against the end of the bearing 36 of the shaft. After the clutch has made a revolution and the lug comes opposite the recess, the clutch members will be pulled apart by the spring 37. The angular movement imparted to the twisting head by one revolution of the shaft 11 can be regulated suitably proportioning the gearing interposed between the shaft and the head.

The jaws will grip the bar until the rear end of the latter has passed beyond the dog 23, which automatically drops permitting the make and break 21 to open and the solenoid to become deenergized. The lever 17 will then be shifted by the spring 25 and open the jaws of the twisting head. It will be observed that dog 23 is located such a distance in front of the rolls, that after the jaws have been opened the rolls will continue to feed the bar sufficiently far to move the portion twisted before the jaws were opened, beyond the jaws and into the larger axial opening through the twisting head and its journal.

In lieu of employing a rotatable head with jaws having their gripping portions corresponding to the cross-sectional contour of the bar, the jaws may have their surfaces

twisted or spirally formed with a pitch corresponding to that of the twist desired in the bar, as shown in Figs. 6, 7 and 8. In such a construction the head 7^a is non-rotatably supported between the forks or arms 38. In the construction shown in Figs. 1 to 5 the inner ends of the jaws or slides 14 are made flat so as to bear uniformly on the sides of the bar. In the construction shown in Figs. 6, 7 and 8 the inner faces of the jaws 39 are spirally formed.

In the construction shown in Figs. 1 to 5 the twist is formed in the bar, between the jaws 14, and the inner or holding portion of the guide 20 and the pitch of the twist given the bar is dependent on the angular movement of the head after the bar is gripped and the distance between the jaws and the inner or holding portion of the guide 20. In the construction shown in Figs. 6, 7 and 8 the rear guide 40 has the cross-sectional shape and dimensions of the bar for its entire length and the twist given the bar is controlled by the pitch of the surfaces of the jaws 39, which have their entering ends enlarged to permit of the easy insertion of the bar. In this construction the jaws are closed before the bar enters and should be opened before the bar has passed from between the rolls, hence only the controlling contacts 21 and their operating dog 23 are required.

I claim herein as my invention:

1. The combination of a rotatable head, jaws movably mounted in the head, rolls arranged to force the bar between the jaws, and means controlled by the bar in its movements for shifting the jaws.

2. The combination of a rotatable head, jaws movably mounted in the head, rolls arranged to force the bar between the jaws, and means intermediate the rolls and head controlled by the bar in its movement for shifting the jaws.

3. In an apparatus for twisting bars, the combination of a rotatable head, jaws movably mounted in the head, rolls arranged to feed a bar between the jaws, and means for opening the jaws arranged in front of the rolls and adapted to be controlled by the bar.

4. The combination of a rotatable head, jaws movably mounted in the head, rolls arranged to force the bar between the jaws and means controlled by the bar in its movement for turning the head and shifting the jaws.

In testimony whereof I have hereunto set my hand.

ROBERT PORTER.
